UNITED STATES PATENT OFFICE.

CHARLES D. RYDER, OF COVINGTON, KENTUCKY, ASSIGNOR TO THE CINCINNATI VICTOR COMPANY, OF CINCINNATI, OHIO, A CORPORATION OF OHIO.

FAN ATTACHMENT.

Application filed October 20, 1927. Serial No. 227,552.

This invention relates to fans, and is particularly directed to a device for controlling the air current created by the fan.

It is an object of this invention to provide a series of vanes arranged in spaced relation in front of the rotary blades of the fan, the vanes being outwardly curved from each side of the central axis of the blades for laterally deflecting a percentage of the air current set up by the fan.

Another object is to assemble these vanes as an attachment device which is readily secured to the cage or guard of the fan.

Still another object is to provide a deflector device of such construction and curvature as to afford efficient lateral deflection of the air current while reducing to a minimum the weight and amount of material used to achieve this result.

Still another object is to provide a deflector device which will supersede the oscillating type of fan.

Further objects and advantages will be more fully set forth in the description of the accompanying drawings forming a part of this specification, in which:

Figure 1 is a front elevation of the fan, showing the deflector device attached to the wire guard or cage of the fan.

Figure 2 is a side elevation of Figure 1 disclosing the attachment means for securing the device to the wire cage or guard.

Figure 3 is an enlarged top view of the deflector device showing it detached from the fan structure.

Referring to the drawings, a type of fan to which the invention may be applied is indicated generally at 1. This fan structure comprises a base 2, a motor 3, rotary blades 4, and a wire cage or guard 5 surrounding the blades and attached to the motor as at 6.

Generally speaking, the device herein concerned comprises an annular frame or ring 7, a parallel series of vanes 8 disposed across the ring, and a plurality of clips 9 secured to the ring for attaching the device to the fan guard. The ring 8 is formed of a length of strap iron bent into a circular shape having its ends joined together as at 10. The various parts may be secured together by any desired means, the preferable means, however, being spot welding.

The vanes 8 are of the same respective curvature and width centrally but decrease in length outward from the center of the

device due to their arrangement within the ring 8. These vanes are preferably formed from thin sheet metal, being perfectly straight on the rear edge 11 and convexly curved on the forward edge 12 from the ends 60 or points of attachment 13 on the ring, thus forming substantially segments of a circle. The ends 13 of the respective vanes are turned inwardly at an angle to correspond to the inner contour of the ring for a snug 65 fit thereagainst.

The vanes as regarded in cross section are curved outwardly in sets from each side of the center of the device, the device and rotary blade shaft 14 being concentric. The 70 arrangement of the vanes across the device is such that there is considerable clearance between each vane for allowing the unobstructed passage of the direct air current between the vanes. The clips 9 are secured 75 to the outer face of the ring and have their inner or attaching ends formed to spring over the outer ring of the fan blade guard. The device may be attached to the fan guard so as to dispose the vanes either horizontally or vertically, or at any intermediate 80 angle, depending upon the required directioning of the diverted air currents.

The deflector vanes as disclosed are mounted on a narrow ring as the body of 85 the device, the ends of the vanes being narrowed down to correspond to the width of the ring, while the central portions of the vanes are of considerable width providing the necessary wide curvature as the deflecting surface. The construction used reduces weight and achieves improved circulation and diffusion of the air current set up by the fan.

Considerable space is provided centrally of 90 the device between the oppositely curved sets of vanes and the vanes of the respective sets are spaced apart. This positioning of the vanes allows the direct air current to pass through in sufficient volume to provide a 100 moderate direct breeze and laterally deflects, through the medium of the vanes, the remainder of the current for air circulation at the sides and forwardly of the fan.

The air from a fan does not leave the fan 105 in the shape of a true truncated cone, but there is a greater concentration of air at the center of the fan than at its edges. It will be seen that my improved deflecting vane is wider at its center than at its ends, and 110

will, therefore, serve to effectively break up this concentration of the air currents by reason of the fact that the air from the center of the fan will be deflected further than that from the portion of the fan adjacent its periphery.

Having described my invention, I claim:

1. In combination with a blade guard of a fan, a deflector, comprising, a ring, a series 10 of vanes secured to and across said ring, said ring being of relatively narrow width, the vanes having wide intermediate deflecting portions and narrow ends attached to the ring, and clips on said ring for detachably 15 securing said deflector to the blade guard.

2. A fan attachment comprising a relatively narrow ring, means to secure said ring to a fan guard, and air deflecting vanes arranged in said ring, said vanes being sub-

stantially segments of a circle, the curved 20 edge of said vanes being arranged away from said fan, whereby said vanes are widest adjacent their centers and decrease in width towards their ends, the ends of the vanes being secured to the ring, and said vanes being 25 curved transversely away from the center of the ring.

3. A fan attachment comprising a series of spaced vanes adapted to be arranged in front 30 of a fan and to extend across the entire face thereof, said vanes being substantially segments of a circle, the vanes being widest adjacent their centers, and decreasing in width towards their ends, said vanes being curved 35 transversely away from the center of the fan.

In witness whereof, I hereunto subscribe my name.

CHARLES D. RYDER.
